(57) **CLAIM**

The ornamental design for a display screen or portion thereof with animated graphical user interface for selection of a food item for cooking in a cooking device, as shown and described.

DESCRIPTION

The patent or application file contains at least one drawing executed in color. Copies of this patent or patent application publication with color drawing will be provided by the Office upon request and payment of the necessary fee.

FIG. 1 is a front view of a first image of a display screen or portion thereof with animated graphical user interface for selection of a food item for cooking in a cooking device; FIG. 2 is a front view of a second image of the display screen or portion thereof;

FIG. 3 is a front view of a third image of the display screen or portion thereof; and,

FIG. 4 is a front view of a fourth image of the display screen or portion thereof.

The appearance of the image transitions sequentially between the images shown in FIGS. 1-4. The broken line showing of the display screen or portion thereof, the text, and the graphic elements form no part of the claimed design.
